UNITED STATES PATENT OFFICE.

JOHN H. EDEN AND GEORGE E. GUTHRIE, OF ESKRIDGE, KANSAS.

FOLDING DESK.

SPECIFICATION forming part of Letters Patent No. 393,364, dated November 27, 1888.

Application filed March 21, 1888. Serial No. 267,979. (No model.)

To all whom it may concern:

Be it known that we, JOHN H. EDEN and GEORGE E. GUTHRIE, citizens of the United States, residing at Eskridge, in the county of 5 Wabaunsee and State of Kansas, have invented certain new and useful Improvements in Folding Desks; and we do hereby declare the following to be a full, clear, and exact description of the invention, such as will enable others skilled in the art to which it appertains to 10 make and use the same.

Our invention consists in the particular construction of folding desk hereinafter to be described and claimed.

15 In the drawings, Figure 1 is a perspective view of a desk embodying our invention. Fig. 2 is a cross-section of the same. Fig. 3 is a similar cross-section showing the book-rack when folded down and locked. Fig. 4 is an 20 elevation of a portion of the desk, showing the book-rack folded down and the lid raised up. Fig. 5 is a detailed horizontal view of a spring- 25 catch on the desk-frame, the frame being shown in section. Fig. 6 is a side view of the same. Fig. 7 is a detail view showing the locking-slot in the book-rack and the knob attached to the lid entering the same. Fig. 8 is the same as Fig. 7, but showing the knob at the 30 moment of insertion.

Throughout the specification and the drawings like reference-letters refer to like parts.

A A' are iron castings supporting the various parts of the desk. These castings are united by the top T and the boards forming 35 the back D into the desk-frame. On the castings A A' are hinged brackets U, which support the boards or slats forming the seat S, and which are prevented from turning too far by the lugs I.

40 The book-rack R is hinged to the top T, as best shown in Figs. 2 and 3. This book-rack is supported in its elevated position by the elbow-braces B B', one end of each of which rests in one of the series of pockets h, formed 45 in the material of the castings A A', while the other end is pivoted to the book-rack R. It is evident that when the elbow-braces are folded up the book-rack will fall to the position shown in full lines in Fig. 3 and in dotted 50 lines in Fig. 7. It is also evident that by resting the end of the brace in one or the other of the series of pockets h the position of the

book-rack and the consequent inclination of the lid which rests upon it may be adjusted at pleasure within certain limits.

5 The lid of the desk consists of the rectangular frame F, having one or more panels, P P'. These panels are pivoted in the rectangular frame by the pivots N N' N'' N''' (best shown in Fig. 4.) These panels may be composed of 6 any two layers of desired substances, so as to present surfaces suitable for any particular purpose. Thus one side, E, Fig. 2, may be of slate, while the other side, C, is covered with the ordinary material for desk-tops. It is evident then that by reversing the panels P P' either of the two surfaces may be brought uppermost for use.

Our preferred apparatus for holding the panels P P' in position is clearly illustrated in 70 Fig. 4. In the end of the panels are mortises V V'. In the rectangular frame bolts W W' slide and enter the mortises V V' when the same are opposite the ends of the bolts. Levers L L' connect these bolts with the spring- 75 pressed plungers w w', so that by pressing on the ends of these plungers the bolts may be withdrawn and the panels revolved. S' indicates the spring which holds the bolt in the mortise until it is withdrawn by pressure upon 80 the plunger w.

As shown in Fig. 3, the lid of the desk is hinged to the top by means of the projecting ears or brackets b b'', and swings about a center which is not coincident with the center 85 about which the hinged book-rack R swings. It is evident, therefore, that as the book-rack and lid fold downward from the position shown in Fig. 2 to that shown in Fig. 3 the lid must slide over the book-rack and change its position relative to the same. We have taken advantage of this fact to cause the motion of the lid to automatically lock itself to the book-rack when the two are folded down. Our preferred construction for doing this is best illustrated in Figs. 4 and 7. A groove, q, is cut 90 in the material forming the end of the book-rack, as shown in Fig. 7. Over this is placed the iron band having the slot Q, as best shown in Fig. 4. Attached to the lid is the knob O, 100 which, when the book-rack is in its elevated position, passes through the wide portion of the slot Q; but as the book-rack is folded down to the position shown in dotted lines in Fig.

7 the knob O is drawn up into the narrow portion of the slot, and the lid is thus automatically locked to the book-rack.

To hold the book-rack in its folded-down position, we employ the apparatus best illustrated in Figs. 5 and 6. Upon the book-rack is the projecting lip M. This is caught by the hooked end of the lever l, pivoted to the frame, as shown in Figs. 2, 3, 5, and 6. Behind the hooked end of the lever l is the spring s', which holds the hooked lever in its outward position of adjustment until it is withdrawn by pressure upon the plunger p. This offers a convenient construction of automatic spring-15 catch for holding the book-rack in its lowest position of adjustment. To lock the same rigidly in this position, the bolt G, operated by the key K in the ordinary manner, may be inserted behind the hooked end of the lever l, 20 thus preventing the elevation of the book-rack and the consequent unlocking of the lid by any one who has not the key that will fit the lock K'.

In the various novel features of this our invention we do not wish to be strictly confined to the exact construction shown, but have illustrated and described the same as our preferred form of apparatus, well knowing that equivalent devices may be substituted therefor which 30 will yet come within the scope of our invention.

Having therefore described our invention, both in essence and detail, what we claim as new, and desire to protect by Letters Patent, 35 is—

1. In a folding desk, the combination of the frame, the book-rack hinged at its upper inner corner to the frame, the lid hinged to the frame and resting on the book-rack, the elbow-40 brace supporting the hinged book-rack, the

series of notches for supporting one end of the brace, the projecting lip upon the book-rack, the hooked lever pivoted to the frame, and the spring and the plunger-bolt for operating the hooked lever, substantially as described. 45

2. In a folding desk, the combination of a stationary frame, a lid which consists of a rectangular frame and a pivoted reversible panel with a spring-catch, hinged to the stationary frame, a book-rack, also hinged to the stationary frame, but on a center not coinciding with that about which the lid turns, the locking slot in the book-rack, and the knob attached to the lid, freely entering and leaving the locking slot at one point in the length 55 of said slot, but retained therein at all other points, substantially as described.

3. In a folding desk, the combination of the frame, the book-rack hinged thereto, the lid, also hinged thereto, but on a center not coinciding with the center about which the book-rack is hinged, the locking-slot in the book-rack, and the knob attached to the lid, freely entering and leaving the locking-slot at one point in the length of the slot, but retained 65 therein at all other points, substantially as described.

4. In combination, the frame, the hooked lever pivoted to the frame, the spring and the plunger-bolt for operating the hooked lever, 70 and the locking-bolt engaging with and holding the hooked lever rigid in one position, substantially as described.

In testimony whereof we affix our signatures in presence of two witnesses.

JOHN H. EDEN.
GEORGE E. GUTHRIE.
